UNITED STATES PATENT OFFICE.

RICHARD J. GREENWAY, OF WESTERLY, RHODE ISLAND, ASSIGNOR TO C. B. COTTRELL & SONS COMPANY, OF STONINGTON, CONNECTICUT, A CORPORATION OF DELAWARE.

ANTIOFFSET MECHANISM FOR PRINTING PRESSES.

Application filed March 3, 1925. Serial No. 12,844.

The object of my invention is to provide certain improvements in the construction, form and arrangement of the several elements of the anti-offset mechanism, where-
5 by the anti-offset powder may be efficiently and thoroughly applied without waste, to the freshly printed side of a traveling web; said elements including a traveling endless belt arranged for contact (preferably ex-
10 tended contact) with the web, means being employed for applying the anti-offset powder in regulable quantities to the endless belt for transfer thereby onto the freshly printed side of the web.

15 A practical embodiment of my invention is represented in the accompanying drawings, in which

Fig. 1 represents in side elevation so much of a printing press as includes my improved
20 anti-offset mechanism.

Fig. 2 represents a longitudinal vertical section through the same.

The web 1 passes between the plate cylinder 2 and impression cylinder 3, the shafts
25 4 and 5 of which cylinders are suitably mounted in the frame 6.

30 The endless belt 7 passes around the drive roll 8 and idler roll 9, the lower portion of which belt travels along in contact with the freshly printed side of the traveling web. These rolls 8 and 9 are suitably mounted in the frame 6.

35 The anti-offset supply fountain is denoted by 10 and its roll 11 is arranged in position to apply the anti-offset powder directly to the traveling endless belt 7.

An adjustable doctor knife 12 is mounted in the fountain 10, in position to regulate the amount of anti-offset powder taken by
40 the fountain roll 11 for transfer to the endless belt 7.

45 The endless belt and the fountain roll are driven at the same surface speed as the traveling web, by providing a train of gears 13, 14, 15, leading from the impression cylinder gear 16.

50 It will be seen that by this arrangement I am enabled to apply the anti-offset powder to the freshly printed side of the traveling web in regulable quantities so that all waste

of the powder may be eliminated and also so that too much powder need not be applied to the freshly printed side of the web, the endless belt at the same time having an extended contact with the traveling web. 55

It is evident that various changes may be resorted to in the construction, form and arrangement of the several parts without departing from the spirit and scope of my invention; hence, I do not intend to limit myself to the particular embodiment herein shown and described, but

What I claim is:—

1. A traveling endless belt, means for passing a web beneath the belt with the 65 freshly printed side of the web in extended contact therewith, and means for applying anti-offset powder to the belt for transfer thereby onto the freshly printed side of the web. 70

2. A traveling endless belt, means for passing a web beneath the belt with the freshly printed side of the web in extended contact therewith, means for applying anti-offset powder to the belt for transfer thereby onto the freshly printed side of the web, and means for driving the belt at the same surface speed as the web. 75

3. A traveling endless belt, means for passing a web beneath the belt with the freshly 80 printed side of the web in extended contact therewith, an anti-offset powder supply fountain, and a fountain roll arranged to apply the powder to the belt for transfer thereby onto the freshly printed side of the 85 web.

4. A traveling endless belt, means for passing a web beneath the belt with the freshly printed side of the web in extended contact therewith, an anti-offset powder 90 supply fountain, a fountain roll arranged to apply the powder to the belt for transfer thereby onto the freshly printed side of the web, and means for driving the belt and the roll at the same surface speed as the web. 95

In testimony, that I claim the foregoing as my invention, I have signed my name this 27th day of February, A. D. 1925.

RICHARD J. GREENWAY.
